CLAIM

The ornamental design for a clip with cutting blade, as shown and described.

DESCRIPTION

FIG. 1 is a perspective view of a clip with cutting blade showing our new design;

FIG. 2 is a top view thereof, the bottom view being a mirror image thereof;

FIG. 3 is a right side view thereof;

FIG. 4 is a left side view thereof;

FIG. 5 is a front view thereof; and,

FIG. 6 is a rear view thereof.
